UNITED STATES PATENT OFFICE

1,980,900

BUILDING CONSTRUCTION

Albert F. Bemis, Newton, Mass., assignor to Bemis Industries, Incorporated, Boston, Mass., a corporation of Delaware

Application February 19, 1931, Serial No. 516,894

22 Claims. (Cl. 72—16)

This invention relates to an improved form of building construction, and more particularly to a novel arrangement of members for defining a wall surface, and cooperating attaching means 5 and adjuncts.

The broad aspects of this invention contemplate the use of preformed members, defining a substantially planar surface, in conjunction with separable interlocking fastening elements comprising complementary parts associated with the structural frame members and the preformed wall members, respectively, whereby the wall members may be readily and accurately secured to the frame to define either an exterior or an 15 interior wall surface.

The more specific embodiments of this invention are particularly distinguished by the provision of panels and/or units having substantially plane outer faces which are aligned with 20 similar faces of adjoining units either to define the wall surface, for example to form the finish of an exterior or interior wall, a ceiling or wall of a building, or to form a suitable backing for the application of an outer finish such as stucco, 25 plaster, clapboards used on the exterior of buildings, or wall board, craftek, tile, paper, veneer, ing, etc., used as interior finish.

Heretofore it has been conventional to provide lathing attached to studs, joists, and the like 30 by suitable fastening means and then to apply plaster to the lathing, or else to employ wall boards formed of plaster, composition, fibrous material and the like, and to secure the wall boards to the supporting grounds by fastening 35 means such as nails. These methods of providing interior finish have involved the fitting and cutting of numerous separate elements such as lathing members, wall boards, and the like, and the securing of these members or boards in place 40 by means of individual fastening elements such as nails. Thus the application of wall finish to the partitions and ceilings of rooms has involved considerable expense due to the necessary expenditure of time upon the part of the workmen and 45 the necessity for care in fitting and fastening elements in place.

In contrast to these expensive and laborious methods of applying wall finish, the present invention affords an arrangement permitting the 50 direct application of pre-manufactured and pre-cut wall elements to the supporting grounds or frame members and their attachment thereto by the employment of interfitting or hooked connections which may have parts associated with 55 the supporting elements, such as studs or joists

or members supported thereby, and complementary parts upon the wall panels themselves. Preferably these complementary parts upon the wall panels are concealed so that the wall may have a continuous unbroken surface and connecting 60 elements are so arranged that panels may be fastened in place by a simple movement of a panel itself.

The present invention is particularly adapted to employment in buildings having standardized 65 wall dimensions which may vary according to a predetermined module, such, for example, as the arrangements disclosed in my copending applications, Serial No. 280,226, filed May 24, 1928, and Serial No. 414,056 filed December 14, 1929. 70 Buildings which are thus constructed with their wall dimensions differing only in accordance with a predetermined module or a multiple of the same are accordingly adapted to receive finish elements 75 which may have definite predetermined dimensions and may be readily applied without cutting. In order to permit rapid assembly of the elements and to avoid cutting and painstaking fitting at the corners, I preferably provide special corner units adapted to cooperate with the wall 80 panels in defining the wall surfaces, for example, both at the vertical and upper horizontal corners of rooms.

In accordance with one aspect of this invention, keying panels are provided to engage marginal portions of adjoining panels, the keying panels being provided with special means for attachment to the supporting frame elements. Preferably the main panels may have rabbeted 85 edges at their margins, the rabbeted edges of adjoining panels cooperating to provide a groove in which a key panel is received. In addition to the frame members to which the panels are connected, it is desirable to provide suitable auxiliary supporting elements for connection to the 90 fastening means carried by the panels; and a further aspect of this invention relates to the arrangement of such auxiliary supporting elements and their connections with the main metal frame elements, such as floor joists. 95

Specific embodiments, chosen for the purpose of illustration, are shown in the accompanying drawings, wherein:

Fig. 1 is a perspective view of a portion of a wall provided with a panel arrangement in accordance with the present invention;

Fig. 2 is a detail of a beam-clip blank which may be employed for securing an auxiliary frame element or ground member to an adjoining portion of the structural wall;

100

105

110

Fig. 3 is a perspective view showing the manner in which the blank of Fig. 2 is formed into a clip;

Fig. 4 is a sectional detail of an arrangement such as shown in Fig. 3, also showing the manner in which wall panels are connected thereto;

Fig. 5 is a perspective view of a portion of one type of a keying strip or panel such as shown in Fig. 4;

10 Fig. 6 is a section on line 6—6 of Fig. 5;

Fig. 7 is a detail view of one type of fastening screw employed in conjunction with the arrangement illustrated in Fig. 4;

15 Fig. 8 is a perspective view of an arrangement somewhat similar to that shown in Figs. 3 and 4, but showing an optional form of connecting means;

Fig. 9 is a perspective view of the keying strip or panel shown in Fig. 8;

20 Fig. 10 is a vertical section of a corner at the intersection of a vertical and a horizontal wall;

Fig. 11 is a horizontal section of a corner at the intersection of the vertical walls;

25 Fig. 12 is a perspective view of a corner arrangement where three walls intersect before assembling the corner unit therewith;

Fig. 13 is a similar view of the same corner arrangement after assembling the corner unit therewith;

30 Fig. 14 is a sectional view of a corner arrangement providing a chase between a vertical and a horizontal wall;

Fig. 15 is a similar view showing the arrangement employed in conjunction with two vertical walls;

35 Fig. 16 is a rear view of a portion of a key panel showing a modified form of interlocking fastening means;

Fig. 17 is a sectional elevation showing the 40 manner of fastening the key panel to a frame member;

Fig. 18 is a section taken on line 18—18 of Fig. 17; and

45 Figs. 19, 20, and 21 are views similar to Figs. 16, 17, and 18, respectively, illustrating another modified form of fastening means.

50 Referring to the accompanying drawings, Fig. 1 is a perspective view of a typical wall arrangement which may be employed according to this invention. The main wall panels 1 comprise inner and outer slabs or laminae 2 and 3 respectively; each inner lamina 2 has a greater width than the corresponding outer lamina 3 and extends beyond the latter at both edges, thus providing rabbets at opposite edges of each panel 1. Obviously the panels may be formed of many suitable materials, but I prefer plaster board formed of a plastic composition, such as gypsum, and provided with face sheets of fibrous material such as paper.

55 Preferably each lamina 2 and 3 comprises a separate piece of plaster board with face sheets of fibrous material upon opposite sides thereof and firmly secured thereto by the crystalline penetrative bonding engagement with its fibrous surface. The laminae are secured to each other by a suitable adhesive such as an animal glue disposed between their adjoining face sheets and dried under suitable pressure. Thus each 60 of the main panels 1 may comprise two layers of plaster composition with a face sheet 5 upon the outer face of the narrower lamina 3 and a face sheet 4 upon the outer face of the wider lamina 2, there being two face sheets 8 and 9 disposed between the plaster layers and adhe-

sively secured to each other. The face sheet 8 of the lamina 2 extends beyond the edge of the narrower lamina 3 to the edge of the board and thus finishes and protects the rabbeted portion of the panel. If desired, the edges of the plaster layers may also be provided with coverings of paper.

65 In their normal assembled relation the panels 1 are disposed with their rabbeted edges juxtaposed, thus cooperating to provide a groove at each side of each panel. Preferably intervening key panels 10 are shaped to fit within these grooves, and have connecting means for engagement with complementary means upon the supporting elements or grounds.

For example, referring to Figs. 4 and 5, it may be seen that the key strip 10 is also formed of plaster board provided with face sheets 11 and 12.

A backing strip 15 of suitable form-retaining material such as wood or metal is adhesively secured to the inner face sheet 12 of the panel 10. Suitable recesses 14 in the plaster board register with a plurality of openings 16 in strips 15, there preferably being two longitudinally disposed rows of these openings and recesses.

90 Openings 16 may conveniently be in the form of keyhole slots and the supporting elements or grounds 23 may be provided with connecting means 25, such as screws. Preferably these screws have their threaded portions dis-

posed substantially within the frame members 23 and have their shanks projecting therefrom through openings 27 which are formed in the marginal portions of the inner lamina 2 of the panels 1 during the manufacture of the latter.

95 Preferably, as shown in Fig. 7, the screws 25 have integral annular flange portions 26 spaced from their heads 28. The screws 25 may be applied to the supporting members 23 and threaded into place until the annular portions 26 engage

100 the surfaces of the marginal portions of the main panels 1. Then the panels 11 may be quickly applied to conceal the screws and to provide a continuous finished surface. For this purpose the enlarged portions 16 of the keyhole slots receive the heads of the screws and the strip 10 is then

105 moved longitudinally so that the shanks of the screws are received in the narrower portions 17 of the slots, the heads of the screws engaging the inner surface of the strip 15. It is evident that

110 this arrangement permits the face sheets upon the outer surfaces of the panels 10 and 1 to be in the same plane so that a substantially continuous surface is defined, which may be employed as the actual finish of the wall or which may

115 receive any suitable decorative treatment.

120 When employing the form of the invention illustrated in Fig. 4, it is desirable to have wooden grounds to permit ready application of the screws 25. Accordingly, Figs. 2, 3, and 4 illustrate an

125 arrangement which may be employed for securing wooden grounds to metal frame members 30 which may, for example, be metal I-beams or joists.

Fig. 2 discloses a metal beam clip blank 31 which may be formed of two strips of sheet metal crossing each other and welded in super-

130 posed relation. One of these strips 32 has symmetrically disposed openings 33 provided adjoining its corners and, as shown in Fig. 3, its end portions are bent downwardly in relation to

135 the main plane of the blank. The other metal strip 34 may have ductile end portions 35 which are bent upwardly and drawn down into firm engagement with the flanges of the I-beam 30, as

140 shown in Fig. 3. Thus the blank is formed into a clip having an inverted channel 36 in which

145

150

the element 23 may be received. Suitable fastening screws 39 may extend through the openings 33 provided in the depending sides of the clip and register with openings in the element 23. The 5 latter, for example, may comprise a metal channel 40 with a wood filler 41 therein, the metal channel having holes 43 to receive the screws 25.

Figs. 8 and 9 show an optional arrangement 10 for connecting the panels 1 to supporting elements of the frame structure such as the members 23. In this form of the invention the keying strip 10^a may be similar to the strip 10 but may be provided with a single row of recesses 16^a and 15 with a corresponding row of keyhole slots 17^a, the keying strip itself and the retaining strip secured thereto being of the same general character as previously described. With this form of the invention, screws 50 may extend between the 20 edges of the panels 1 and may have head portions 51 adapted to engage the keyhole slots 17^a, the panels 1 being pressed upwardly as the keyhole slots are thus engaged with the screw heads and the latter being depended upon to support 25 both the panels 1 and the panels 10^a. Thus in this form of the invention the special type of screw illustrated in Fig. 7 may be dispensed with if desired.

While Figs. 4 and 8 particularly illustrate my 30 panel arrangement as applied to ceilings, the same may be readily employed for vertical walls or partitions and may be connected to the wall elements or studs in the same general manner as described with reference to Figs. 4 and 8.

35 The arrangements shown in Figs. 16 to 21, inclusive, dispense with the use of the fastening elements 25 by providing interlocking fastening means integral with the key panel. The structure of the key panel is generally similar to the 40 one previously described and shown in Figs. 4 and 5, and comprises a lamina 10^b preferably of plaster board provided with fibrous face sheets 11 and 12. A metal backing strip 15^b having struck out tabs or tongues is adhesively secured 45 to the inner face sheet 12. The tongues 21 may be bent outwardly and downwardly to provide hooked portions, as shown in Figs. 16 and 17, or as shown in Figs. 19 to 21, the tongues 21^a having a depending portion may simply be bent 50 outwardly to provide hooked connections. In both embodiments the frame members 23^a are provided with openings 22 which receive the tongues of the backing strips and thus provide an interlocking fastening means which permits 55 the wall panels 1 to be assembled with the frame elements in the same manner as previously described. In the embodiment shown in Figs. 16 to 18, it is preferable to provide the rabbeted end portions of lamina 2 with openings for the reception of the shank portions of the tongues, and in the embodiment shown in Figs. 19 to 21, recesses or notches in the lamina serve the same purpose. It is obvious that these key panels may 60 be quickly and securely assembled with the panel and frame members merely by inserting them in the grooves so that the cooperating interlocking elements engage, and by a slight longitudinal movement the same are firmly and securely locked in place.

70 At the corners or intersections of either horizontal walls or vertical and horizontal walls, I provide special preformed corner members or panels which are adapted readily to fit into place and to be connected to the adjoining structure. 75 Fig. 10 shows such an arrangement at the in-

tersection of a horizontal wall or floor and a vertical wall. An angular sheet metal member 60 may be provided to define this corner, having an offset marginal flange 61 to extend over the adjoining edge of a key strip 10 in the ceiling, which is disposed beneath supporting element 23 and the opposite edge of which engages the panel 1 at the end of the ceiling assembly. A filler strip 65 of plaster board may be disposed above flange 61. It is evident, as shown in Figs. 80 10 and 12, that the surface of the panel 60 thus may provide a substantial continuation of the outer surfaces of panels 1 and 10. The depending vertical portion 63 of the member 60 may fit against the adjoining surface of the wall so that there is no substantial break in the continuity of the wall surface, it being understood that the member 60 is formed of comparatively thin gauge metal. If desired screw-fastenings 85 64 may secure the depending portion 63 of member 60 to the vertical wall.

Fig. 11 shows the arrangement at the intersection of vertical walls or partitions, a metal corner member or panel 70 being arranged to define the corner surfaces in alignment with the main surfaces of the wall and having offset portions 71 disposed behind adjoining edges of the key strips 10 at the ends of the panel assemblies upon the intersecting walls. The opposite edges of these key strips engage the outstanding marginal portions of the end panels 1, as shown, and small filler strips 73 of plaster board may be disposed between the offset portions 71 and the grounds 75 which may form a part of any suitable wall structure.

Fig. 12 shows the unfinished corner construction at the junction of the ceiling and vertical walls, the corner members or units 60 and 70 defining, respectively, the intersection between the ceiling and walls and the intersection between the vertical walls, previously described in connection with Figs. 10 and 11. Fig. 13 shows the finished corner structure formed by assembling the corner member 80 therewith. This member is preferably of sheet metal having faces in three planes defined by the walls and ceiling, and having the marginal portions of its faces overlapping the adjacent portion of the corner members and wall panels. Suitable retaining screws 81 may be employed to secure this corner piece in 125 place.

Fig. 14 shows an arrangement providing a cornice chase at the intersection of the ceiling and a vertical wall. In this particular arrangement, the member 90, defining the chase, is provided with marginal flanges 91 and 92, the flange 91 being interposed between the key strip 10 and the projecting edge of the rabbeted ceiling panel, and flange 92 overlapping the marginal portions of the adjacent wall panels. The details of the flange construction and manner of assembly with the wall and ceiling panels are, in general, the same as previously described in connection with the preformed corner member shown in Fig. 10. Fig. 15 shows a similar arrangement at the intersection of the vertical walls or partitions. The member 100 defining the vertical cornice chase has flanges 101 interposed between and retained by the key strips and projecting ends of the wall panels. The manner of assembly with the adjacent wall panels is similar to that described in connection with the corner member shown in Fig. 11.

From the foregoing it is evident that I have provided an improved arrangement of wall panels 150

and fastening means therefor which particularly permit the employment of preformed panels without necessity for cutting in situ and which permit the facile attachment of the panels to the supporting grounds and their ready assembly with each other. These panels may not only be quickly applied and may be adapted to form the actual finish of the room, but they also may receive any suitable finishing treatment and, if desired, they may be so arranged and finished that they may be readily removed to permit access to the interior of the wall, for example, to permit the repair of heating ducts, pipes, or inspection of electrical conduits.

15 While I have shown and described certain embodiments of this invention, I wish it to be understood that various modifications and changes in shape, proportion, and arrangements of parts, as well as the substitution of equivalent elements for those herein disclosed, can be made without departing from the spirit and scope of the invention as set forth in the appended claims.

I claim:

1. A building construction comprising frame members, panel members defining the face of a wall, the end portions of each of said panel members being rabbeted to provide grooves on the outer face of the wall portion, key panels disposed in said grooves, and interlocking fastening means detachably securing said panel members and key panels in assembled relation to the frame members, said means being shaped to provide hook-like connections disposed so that the panels may be detached from the wall by sliding the key panels longitudinally in their grooves.

35 2. A building construction comprising frame members, panel members defining the face of a wall, alternate panel members having marginal portions overlapping those of the intervening panel members, the latter portions having openings, and means associated with the alternate panel members and frame members securing said panel members in assembled relation with the frame members, said means comprising separable interlocking elements having portions passing through said openings in the intervening panel members.

50 3. A building construction comprising frame members in intersecting walls, panel members defining the faces of a wall and ceiling, the end portions of the ceiling panels adjacent to the intersection of the planes of the wall and ceiling being rabbeted, a corner panel having faces in the plane of the wall and the plane of the ceiling, said corner panel having an offset end portion disposed in overlapping engagement with the rabbeted portions of the ceiling panels and defining therewith a groove, the opposite end portion being disposed contiguous to the end portions of the wall panels, fastening elements securing said ceiling panels and corner panel to the frame members, and a key panel disposed in said groove, said key panel having interlocking means cooperating with said fastening elements and securing the key panel in assembled relation with the ceiling panels and corner panel.

65 4. A building construction comprising frame members in intersecting walls, panel members defining the faces of the walls, the end portions of said panels adjacent to the intersecting planes of the walls being rabbeted, a corner panel having faces in the plane of the walls, said corner panel having offset end portions disposed in overlapping engagement with the rabbeted portion of the panel members and defining there-

with grooves, fastening elements securing said panel members and corner panel to the frame members, and key panels disposed in said grooves, said key panels having interlocking means cooperating with said fastening elements and securing the key panels in assembled relation with the panel members and corner panel.

5. A building construction comprising walls and a ceiling in intersecting planes, panel members defining the faces of the walls and ceiling, corner panels defining the junction between each wall and ceiling and the intersecting walls, and a corner unit having faces in the planes of the walls and ceiling, the marginal portions of said corner unit being disposed contiguous to the adjacent marginal portions of the corner panels and defining therewith substantially planar surfaces.

6. A building construction comprising frame members, panel members defining intersecting walls, said panel members having rabbeted end portions, a cornice chase member having an integral flange engaging said rabbeted end portions and defining therewith a groove, and a filler panel disposed in said groove.

7. A corner assembly comprising frame members, panel members defining intersecting walls, said panel members having rabbeted end portions, a cornice chase member having integral flanges engaging said rabbeted end portions and defining therewith a groove, fastening elements securing the panel members and cornice chase to the frame members, and filler panels disposed in said grooves, said filler panels having interlocking means cooperating with said fastening elements to secure the filler panels in assembled relation with the panel members and cornice chase member.

8. A building construction comprising a frame member, a panel member having a surface to define the plane of a wall, and fastening means securing the panel member to the frame member, said means being in the form of pairs of complementary interlocking portions shaped to afford a hook-like engagement so that the panel member may be detached from the frame member by a sliding movement of the panel member.

9. A building construction comprising wall structure, a panel member mounted on the wall structure, and fastening means securing the member to said structure, said means comprising pairs of interfitting elements, one element of each pair affording a projection with an enlarged end and the cooperating element affording a slot to receive the enlarged end of the projection in engagement with an edge of the slot.

10. A building construction comprising a wall structure, panel members mounted on the wall structure and having margins overlapping the margins of intervening panel members, fastening means securing the first-named panel members to the wall structure, said means being in the form of complementary interlocking elements shaped to afford a hooklike engagement and being capable of manual separation by a simple manual movement of the corresponding panel substantially in its own plane, whereby the intervening panels may be released from the wall structure.

11. A building construction comprising a wall structure, panel members mounted on the wall structure, fastening means securing the panel members to the wall structure and including complementary fastening elements constructed and arranged so that the panels may be separated

30

145

150

from the wall structure by a longitudinal sliding movement, the panels being arranged so that there is a clearance at their ends to permit such a movement, and a finish strip extending along the ends of the panels to conceal the clearance space.

12. A building construction comprising a wall structure, panel members mounted on the wall structure, fastening means securing the panel members to the wall structure and including complementary fastening elements constructed and arranged so that the panels may be separated from the wall structure by a longitudinal sliding movement, the panels being arranged so that there is a clearance at their ends to permit such a movement, and a finish strip extending along the ends of the panels to conceal the clearance space, said finish strip being secured to the ends of the panels to hold them in relative alignment against endwise movement until the finish strip is detached from the panels.

13. A building construction comprising a wall structure, a plurality of panels mounted on the wall structure and quick detachable fastening means securing the panels to the wall structure, said means including a plurality of pairs of complementary elements, one element of each pair being arranged to provide an opening with a slot-like continuation and the other element providing a projecting portion with an enlargement received in the opening and slideable into engagement with the slot-like continuation, whereby the panels may be disengaged from the wall structure by sliding movements of the panels to effect the relative positioning of the elements so that the enlargements of said projecting portions may be removed through the openings.

14. A building construction comprising a wall structure, a plurality of panels mounted on the wall structure, and fastening means securing the panels to the wall structure, said fastening means comprising pairs of complementary elements in the panels and wall structure, one element of each pair affording an opening, the complementary element of the pair providing a projection with a hook-like end portion to engage the edge of the opening, the panels being slideable relative to the wall structure to effect the relative disengagement of the hook-like end portions of said projections and said openings, whereby the panels may be separated from said structure.

15. A building construction comprising a wall structure, a plurality of panels detachably mounted on the wall structure, fastening means securing the panels to the wall structure and including a plurality of pairs of complementary fastening elements, one element of each pair being in the form of a plate secured to the panel and providing an opening, the complementary element of the pair being in the form of a screw fastener threaded into the wall structure, said screw fastener having a head portion and an integral part spaced from the head portion acting as a stop limiting the movement of the fastening element when it is screwed into the wall structure, whereby the head portion provides an enlarged protuberant part adapted to have a hook-like engagement with the opening in said plate.

16. A building construction comprising a wall structure, a plurality of panels mounted on the wall structure and including key panels and intervening panels, the intervening panels being formed of two layers of material having their margins offset to afford rabbets at the margins of said intervening panels, the adjoining rabbeted

margins of said intervening panels cooperating to define a groove, a key panel being disposed in each of the grooves and comprising a layer of material substantially coplanar with the outer layer of material in the intervening panels and quick detachable fastening means associated with the key panels to secure all of the panels in place.

17. A building construction comprising a wall structure, a plurality of panels mounted on the wall structure and including key panels and intervening panels, the intervening panels being formed of two layers of material having their margins offset to afford rabbets at the margins of said intervening panels, the adjoining rabbeted margins of said intervening panels cooperating to define a groove, a key panel being disposed in each of the grooves and comprising a layer of material substantially coplanar with the outer layers of material in the intervening panels and quick detachable fastening means associated with the key panels to secure all of the panels in place, said fastening means including screws screwed into the wall structure through the openings in the rabbeted end portions of the intervening panels, said screws having integral stop portions spaced from their heads and engaging the outer surface of the inner layer of the intervening panels and having their heads disposed outwardly of said inner surface, the key panels being provided with recesses adapted to have a hook-like engagement with the heads of said screw elements, whereby each key panel may be removed from the wall structure by a sliding movement in its own plane and whereby the intervening panels may be removed by unscrewing the screw elements from the wall structure.

18. A building construction comprising a wall structure, paneling mounted on the wall structure and including main panels formed of inner and outer layers of plaster board secured to each other to afford panels having rabbeted edges, the rabbeted ends of said main panels cooperating to provide grooves, key panels disposed in said grooves and comprising a single layer of plaster board substantially in coplanar relationship with the outer layer of plaster board in the main panels, and fastening means associated with the key panels and the rabbeted ends of the main panels to secure the paneling to the wall structure, said fastening means being concealed by the key panels.

19. A building construction comprising a wall structure, paneling detachably mounted on the wall structure, said paneling including a plurality of intervening panels, said panels having rabbeted margins engaging key panels disposed between the intervening panels, said key panels having backing plates of metal with integral hook-like tongue portions, the wall structure being provided with means affording recesses to receive the hook-like portions of the backing plates whereby the key panels are held in place upon the wall structure and engage the rabbeted margins of the intervening panels to hold the latter against the wall structure, the panels being removable from the wall structure by a sliding movement of the key panels substantially in their own planes to disengage the hook-like tongues from the openings provided in the wall structure.

20. A building construction comprising wall structure disposed in intersecting planes, paneling mounted on the wall structure, said paneling including a plurality of main panels having rab-

21. A building construction comprising a wall structure, a plurality of panels mounted on the wall structure and including key panels and intervening panels, the margins of the intervening panels being rabbeted to provide grooves in which the key panels are received, fastening means provided by the key panels and said structure shaped to permit detachment of each key panel by longi-
